(57) **CLAIM**

The ornamental design for a fluid pressure cylinder, as shown and described.

DESCRIPTION

FIG. 1 is a front view of a fluid pressure cylinder showing our new design;

FIG. 2 is a rear view of the fluid pressure cylinder;

FIG. 3 is a top view of the fluid pressure cylinder;

FIG. 4 is a bottom view of the fluid pressure cylinder;

FIG. 5 is a right side view of the fluid pressure cylinder;

FIG. 6 is a left side view of the fluid pressure cylinder;

FIG. 7 is an enlarged cross-sectional view of the fluid pressure cylinder taken along line 7—7 of FIG. 1; and,

FIG. 8 is a perspective view of the fluid pressure cylinder.

The broken lines in the drawing are for the purpose of illustrating portions of the fluid pressure cylinder that form no part of the claimed design.
